CLAIM

I claim the ornamental design for a caution sign, as shown and described.

DESCRIPTION

FIG. 1 is a front view of the caution sign.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a front view of the claimed design as it appears on a vehicle.

The broken lines appearing on FIG. 7 of a vehicle are environmental matter forming no part of the claimed design.
